UNITED STATES PATENT OFFICE.

BENJAMIN H. LOUTHAIN AND STEWART G. HONECK, OF MILWAUKEE, WISCONSIN.

DESIGN FOR A STATUETTE.

Application filed April 25, 1923. Serial No. 5,938. Term of patent 3½ years.

To all whom it may concern:

Be it known that we, BENJAMIN H. LOUTHAIN and STEWART G. HONECK, citizens of the United States, residing at Milwaukee, in the county of Milwaukee and State of Wisconsin, have invented a new, original, and ornamental Design for Statuette, of which the following is a specification, reference being had to the accompanying drawing, forming part thereof.

The drawing shows the statuette in perspective.

We claim:

The ornamental design for a statuette, as shown.

BENJAMIN H. LOUTHAIN.
STEWART G. HONECK.
